UNITED STATES PATENT OFFICE

110,364

DESIGN FOR AN AIRPLANE

John B. Reinhard and Lynn J. Koch,
Allentown, Pa.

Application January 28, 1938, Serial No. 74,692

Term of patent 14 years

To all whom it may concern:

Be it known that we, John B. Reinhard and Lynn J. Koch, citizens of the United States, residing at Allentown, in the county of Lehigh and State of Pennsylvania, have invented a new, original, and ornamental Design for an Airplane, of which the following is a specification, reference being had to the accompanying drawing forming part thereof.

In the drawing, Figure 1 shows in side elevation, an airplane embodying our new design;

We claim:

The ornamental design for an airplane, as shown.

JOHN B. REINHARD.
LYNN J. KOCH.
